UNITED STATES PATENT OFFICE.

JOSEPH HEAD, OF YORK, PENNSYLVANIA.

TAN-VAT.

SPECIFICATION forming part of Letters Patent No. 380,890, dated April 10, 1888.

Application filed February 12, 1887. Serial No. 227,418. (No model.)

To all whom it may concern:

Be it known that I, JOSEPH HEAD, a citizen of the United States, residing at York, in the county of York and State of Pennsylvania, have invented certain new and useful Improvements in Agitators; and I do hereby declare the following to be a full, clear, and exact description of the invention, such as will enable others skilled in the art to which it appertains to make and use the same.

My invention relates to certain improvements in tan-vats.

The object I have in view is to improve the agitators used in connection therewith, the improvements in said agitators consisting both in their construction and in their position with respect to the floating frame ordinarily used for carrying the hides to be operated upon.

In the further description of the invention reference will be made to the accompanying drawings, in which—

Figure 1 is a view in perspective of the hide-supporting frame and its parts, including the agitators; and Fig. 2 a longitudinal section 25 through the vat with parts in position.

Like letters refer to like parts in each view. A represents the vat, which is of ordinary construction, and which is provided on its interior with four corner-posts, A', each one of 30 which extends from the bottom of the vat to a point within a short distance of the top thereof, said parts serving as guides to the hide and agitator supporting frame, and also as stops to limit the movement of such frame 35 downwardly. This hide-supporting frame consists of an upper frame, B, the longitudinal bars of which are notched, as shown, to receive the cross-strips a, upon which the hides are hung, and two bottom pieces, B', the top 40 frame and bottom pieces being connected by suitable uprights, B''. The bottom pieces, B', are shorter than the longitudinal boards of frame B, and the uprights B'' are therefore placed on an incline, as shown in Fig. 2. The 45 uprights are also connected near their lower ends by cross-boards B³, which form bearing-points for the agitators now to be described.

By reference to the drawings, especially Fig. 1, it will be seen that two styles of agitators have been shown. In connection with the one 50 marked C, I use a strip, C', situated at or about its center, there being secured to said strip a vertical rod, C'', passed up through one longitudinal board of frame B and formed into a suitable handle. As shown, this rod is thus 55 connected with one side edge of the agitator, while the pivot or bearing points b thereof are in the opposite edge at each end, whereby the elevation or depression of said rod will serve to operate said agitator. The second style of 60 agitator (marked D) consists of a board with trunnions c at the center of each end and provided near each side edge of one end with suitable rings, d, to each of which one end of a rope, D', is secured, said rope passing up to 65 the top of the vat and serving as a medium for operating such agitator, when desired. On the top of one end of frame B a suitable pin or stud, e, may be provided for holding the rope 70 when not in use.

It will be understood that when the vat is provided with the liquid this whole framework B C, together with the agitator, will float on its surface, as the hide-supporting frame ordinarily does.

What I claim is—

The combination, with a tan-vat, of a floating hide-supporting frame consisting of a top frame, B, notched to receive the hide-supporting cross-strips a, a bottom frame, B', connected to the upper frame by inclined uprights B'', and cross-pieces B''', connecting said uprights, and agitators C and D, pivoted at their ends in said cross-pieces and provided with a rod or rope, whereby they may be vibrated, substantially as described.

In testimony whereof I affix my signature in presence of two witnesses.

JOSEPH HEAD.
